SWITCH

Albert Bolduc, Detroit, Mich.

Application July 6, 1934, Serial No. 733,982

3 Claims. (Cl. 240—10.68)

This invention relates to improvements in a switch and particularly in a switch of the type used on small flashlights.

A primary object of this invention is to provide an improved device of the above nature wherein a member, adapted to receive a light bulb, may be rotated to perform the function of a switch for said bulb.

Another object of this invention is to provide a device of the above nature, wherein the construction may be noted for its simplicity and compactness.

Further objects and advantages of the present invention will be apparent from the following description, reference being had to the accompanying drawing wherein a preferred embodiment of one form of the present invention is clearly shown.

In the drawing:

Fig. 1 is a sectional view on line 1—1 of Fig. 2; Fig. 2 is a longitudinal sectional view on line 2—2 of Fig. 1;

Fig. 3 is a sectional view on line 3—3 of Fig. 4, showing the light bulb receiving member rotated 25 in contact position.

Fig. 4 is an outside view of a flashlight embodying the present invention.

In the drawing, 12 designates a tubular metal casing closed at one end, and adapted to receive a dry cell 19, a spring 20 and a subassembly comprising a light bulb 10, bushing 14, retaining washers 17 and 18, a resilient member 16, and a socket 11.

The light bulb 10 is axially guided in socket 11 by a non-conducting bushing 14 and held in place by non-conducting eccentric washers 17 and 18. Bushing 14 and washers 17 and 18 are pressed into socket 11. Resilient member 16 is laterally compressed within socket 11, and is so shaped as to provide a spring contact 24 which bears on the threaded portion of bulb 10 when switch is making contact; the resilient member 16 has another portion of its body formed into a semi-spherical projection 22 which slips thru an opening 21 in socket 11 and slides into an internal annular groove 15 formed in casing 12.

Socket 11 may be readily removed from casing 12 by applying an axial pull of sufficient force to overcome the pressure exerted by the resilient member 16 against the inner surface of groove 15.

It will be noted that the resilient member 16 also serves the purpose of preventing socket 11 from falling out of casing 12 thru the constant engagement of projection 22 in annular groove 15.

In the "Off" position, projection 22 enters into cavity 13 formed in annular groove 15 of casing 12, thereby allowing spring contact 24 to retract from threaded portion of bulb 10 and break contact.

While the form and embodiment of the present invention as herein disclosed, constitutes a preferred form, it is to be understood that other forms might be adopted, all coming within the scope of the claims which follow.

What is claimed is as follows:

1. In a switch of the class described, the combination comprising; a tubular member having an internal annular groove partially deepened on its circumference; a circular resilient current carrying member having a portion of its body extending into said groove, said resilient member having another portion of its body adapted to bear against the external cylindrical metallic portion of a light bulb; means for rotating said resilient member including a socket adapted to receive and insulate said bulb.

2. In a switch of the class described, the combination comprising; a tubular member closed at one end, adapted to receive a dry cell, means for establishing contact between the dry cell and said tubular member, said tubular member having an internal annular groove partially deepened on its circumference; a circular resilient current carrying member having a portion of its body extending into said groove, said resilient member having another portion of its body adapted to bear against the external cylindrical metallic portion of a light bulb; means for rotating said resilient member including a socket adapted to receive and insulate said bulb.

3. In a switch of the class described, a socket comprising; a rotatable sleeve adapted to receive a guide for a light bulb, a retainer for said bulb including two eccentric washers overlapping each other and of a thickness suitable to provide a receptacle for threaded portion of said light bulb, a space between said guide and said retainer to allow free movement of a current carrying member.
